UNITED STATES PATENT OFFICE.

FRANK MONTGOMERY, OF PORT ARTHUR, TEXAS.

WATER DRAWER.

Application filed June 23, 1923. Serial No. 647,385.

To all whom it may concern:

Be it known that I, FRANK MONTGOMERY, a citizen of the United States, and resident of Port Arthur, in the county of Jefferson 5 and State of Texas, have invented certain new and useful Improvements in Water Drawers, of which the following is a specification.

This invention relates to automatic water 10 drawers especially adapted for use in automatically drawing the water from beneath the oil in the oil containing tanks of refineries.

This invention is an improvement over 15 the construction illustrated in my co-pending application Serial No. 594,160, filed Oct. 12, 1922, and is especially designed with a view of simplifying the construction, maintenance and operation.

20 Other objects and advantages will be apparent during the course of the following description.

In the accompanying drawing forming a 25 part of this application and in which like numerals are employed to designate like parts throughout the same,

Figure 1 is a longitudinal sectional view 30 through an automatic water drawer constructed in accordance with the invention and applied to an oil tank.

Figure 2 is a perspective illustrating the connection between a pair of levers embodied in the invention.

Figure 3 is a side elevation of an oil 35 containing tank equipped with the improved automatic water drawer parts being shown in section.

Figure 4 is a sectional view through a slight modification of the invention.

40 In the drawing the numeral 5 designates a container attached to and having communication with the oil tank 4 and by reference to Figure 1 it will be seen that the outlet member 6 of the receptacle has its upper portion formed with a valve seat 7 with which a valve 8 is adapted to cooperate. More 45 specifically the lower portion of the valve 8 is cone-shaped as indicated at 10 and is adapted to flatly contact with the inclined seat 7 so as to control the flow of liquid.

50 Figure 1 illustrates that a pair of standards 14 are arranged in the container at points spaced from the center thereof and have their upper portions pivotally connect- 55 ed to levers 15 as indicated at 16. The ad-

jacent portions of the levers 15 are overlapped and are formed with registering slots 18 to slidably receive a connecting pin 19 so that movement of one lever is transmitted to the other lever.

60 One of the levers 15 is provided with a float 20 having a link 21 pivotally connected to one of the levers 15 as indicated at 23 and it will be seen that the density of the liquid or the level of the same in the tank will control the position of the float 20 and the position of the float 20 in turn controls the position of the valve 8. The upper portion of the valve 8 has connection with a link 25 and the link 25 is in turn connected to the outer end of one of the levers as indicated at 26.

65 From the foregoing description it will be seen that the level of the liquid in the container 5 controls the position of the float 20 and the float 20 in turn automatically controls the valve 8 so that the discharge of water is automatically controlled.

70 In carrying out the invention the container 5 may be provided with a drain cock 30 by means of which sediment or the like may be discharged. Also a screen or other filtering medium may be employed between the container 5 and the machinery to eliminate trash or foreign matter which would be likely to interfere with the operation of the 75 valve 8.

76 In the form of the invention illustrated in Figures 1, 2 and 3 the container 5 is formed at its upper portion with a flange 170 which may be attached by bolts, rivets or other suitable means to the bottom of the main oil container 4. Of course, preparatory to attaching the receptacle or container 5 to the bottom of an oil tank the bottom of the oil tank is provided with an opening large 80 enough to provide free and unrestricted communication between the tank and the automatic water drawer. A suitable screen 172 extends across the top of the automatic water drawer and excludes foreign matter of a greater specific gravity than the oil and water.

85 In operation the water beneath the oil will raise the float 20 due to the specific gravity of the same and more particularly the difference in the specific gravity of the float 20 and the specific gravity of the water. When the water actuates the float 20 the valve 8 will be elevated so as to allow the water beneath the oil to be drawn off through the dis- 90 95 100 105 110

- charge member 6. When the water is discharged the float 20 will return to its normal position and thereby prevent the oil from accidentally being discharged.
- 5 In the form of the invention illustrated in Figure 4, the container 180 is attached to the oil containing tank 181 through the medium of a pipe 182, the said pipe being provided with gate valves 183 and 184, both 10 of which control communication between the container 180 and the tank 181.

The inlet end of the pipe 182 is extended downwardly as indicated at 186 and is extended into a recess portion 187 in the bottom of the oil tank so as to receive all the 15 water in the tank.

The container 180 is provided with a liquid controlling mechanism 185 similar to the liquid controlling mechanism illustrated 20 in Figure 1 and the said liquid controlling mechanism of course controls the discharge of water through a discharge pipe 186 in the bottom of a well 187 in the container 180. Attention is directed to the fact that an 25 emergency drawer pipe 190 is located between the valves 183 and 184 and is provided with a valve 192 by means of which the emergency discharge of liquid is controlled. By locating the valve 192 and the emergency 30 drawer pipe 190 between the valves 183 and 184, a positive control is provided and the liquid may be directed through the pipe 182 and into the container 180 without being discharged through the emergency drawer 190. 35 This is possible because of the arrangement of the several valves.

In carrying out the invention a vent pipe 196 is extended upwardly from the container 180 and is provided with a lateral branch 40 communicating with the main tank 181 to form a means whereby the oil may be returned to the tank.

With reference to the foregoing description taken in connection with the accompanying drawings, it will be apparent that 45 the automatic water drawer illustrated and described is especially adapted for use in automatically withdrawing the water beneath the oil in the oil containing tank so that the pressure of an attendant is unnecessary.

In carrying out the invention any desired leverage may be employed in connection with the members and preferably the ratio 50 of 6 to 1 is employed in connection with a ten gallon power float. A varied range of power can be obtained in using a ratio of 4 or 6 to 1 and the power float from one gallon up.

Having thus described the invention, what is claimed is:—

1. The combination with a container, of standards arranged therein, separate levers pivoted to the standards and having their adjacent portions overlapped and slidably 65 and pivotally connected, a valve connected to one of the levers, and a float connected to the other lever and controlled by the liquid within the tank.

2. The combination with a container, of 70 standards arranged at spaced points therein, levers pivoted to said standards and having their adjacent portions overlapped and pivotally and slidably connected, links connected to the outer ends of said levers, a valve 75 connected to one of the links, a float connected to the other link and constituting the main regulating medium, and a drain member connected to the bottom of the container.

3. The combination with a container, of 80 standards arranged at spaced points therein, levers pivoted to said standards, links connected to the outer ends of said levers, a valve connected to one of the links, a float 85 connected to the other link and constituting the main regulating medium, a drain member connected to the bottom of the container, and an outlet member controlled by said valve, one of said levers having its inner terminal portion forked to provide legs arranged on opposite sides of and overlapping the other levers, and means slidably and pivotally connecting the overlapped portions of said levers.

4. An automatic water drawer comprising 90 a liquid containing tank, a container having a pipe extending into the lower portion of the tank, valves interposed in the pipe, an automatic discharge controlling device located in said container, a discharge pipe 100 connected to said container and controlled by said automatic discharge controlling device, and an emergency drawer connected to said pipe, between said valves.

5. An automatic water drawer comprising 105 a liquid containing tank, a container having a pipe extending into the lower portion of the tank, valves interposed in the pipe, an automatic discharge controlling device located in said container, a discharge pipe 110 connected to said container and controlled by said automatic discharge controlling device, an emergency drawer connected to said pipe between said valves, and a vent pipe 115 connected to said container and having a branch communicating with said tank.

FRANK MONTGOMERY.
